HALVOR ANDRESEN, OF NEW YORK, N. Y., ASSIGNOR TO THE VACUUM MUFFLER CORPORATION.

MUFFLER.

1,272,180.

Specification of Letters Patent. Patented July 9, 1918.

Application filed June 26, 1917. Serial No. 177,067.

To all whom it may concern:

Be it known that I, HALVOR ANDRESEN, a subject of the King of Norway, and a resident of the borough of Manhattan, in the city of New York, county and State of New York, have invented new and useful Improvements in Mufflers, of which the following is a specification.

The invention relates to mufflers for use with internal combustion engines or in fact for use with any engine or device that has an intermittent discharge into an atmosphere having a lower pressure than that of the discharge.

An object of the invention is to construct a muffler so that the incoming gases will first enter a central initial receiving space that is located within the central portion of the muffler casing and so that the gases passing from this chamber or initial receiving space will flow between outwardly and forwardly extending members into an outer receiving space or conduction chamber which increases gradually in cross-section in passing toward the discharge opening of the muffler.

The outwardly and forwardly extending members—frequently hereinafter referred to as deflecting members or plates—gradually recede from each other in passing from the central portion of the muffler toward the muffler discharge opening. This receding from each other is gradual and relatively small, due to the angle which each deflecting member as a whole makes relatively to the radial line passing through the center of the initial receiving space and the inner or rear end of each member. The forward or outer or discharge ends of the members are arranged in the form of a circle about the center of the initial receiving space and each of these ends makes a comparatively small angle with the line indicating the general direction or flow of gases that travel along through the conduction chamber on the way to the discharge opening of the muffler. These outwardly and forwardly extending members in effect constitute nozzle members. The gases passing from one nozzle thus formed will flow past the delivery end of the succeeding nozzle and will tend to suck gases from the succeeding nozzles.

Further functions and advantages of my

improved muffler construction will herein- 55 after more fully appear.

As illustrating a specific embodiment of the invention reference is made to the accompanying drawing which forms a part of this specification and in which drawing, 60

Figure 1 is a vertical cross-sectional view taken as on the line 1—1 of Fig. 2 looking in the direction of the arrows.

Fig. 2 is a vertical longitudinal-sectional view taken as on the path indicated by the 65 broken line 2—2 of Fig. 1.

Fig. 3 is a sectional-plan view taken as on the line 3—3 of Fig. 1 looking in the direction of the arrows.

The muffler embraces a suitable casing 70 which may be considered to comprise spaced heads A and B and a side wall C. The head A may be arbitrarily referred to as the rear head and the head B as the forward head since the incoming gases first pass through 75 head A and flow forwardly toward head B. This nomenclature, however, it will be understood is as above indicated merely an arbitrary one which is adopted for convenience in this case. The side wall C may 80 be considered to start at 1 continue along a curved path to 2, 3, 4, X¹, 5, 6 and finally return to 1, thereby forming an inclosed exterior curved side wall. This curved side wall C can be formed partially on the head 85 A as, for instance, of the portion ca, and partially on the head B as of portion cb. It will be readily appreciated, however, that the side wall C can be an independent member placed between the opposing heads. 90

In the construction shown the side wall portion cb is provided with a rib cc which enters a groove cd in the side wall portion ca. This side wall C is spiral in form, as will be noted from an inspection of Fig. 1 95 of the drawing. The head A is provided with a tubular projection D to which the exhaust pipe of a hydrocarbon engine may be connected and the incoming gases flow through the inlet opening IN of the tubular projection D into the central chamber or initial receiving space E located within the central portion of the muffler casing. The forward end of this initial receiving space E is defined by a conical portion F 100 which extends rearwardly from the forward head B so that the apex f of said cone F 105 extends into the receiving space E. This

conical portion F serves to turn and deflect laterally the incoming gases, which are traveling forwardly in a longitudinal direction, and this turning or deflecting of 5 the incoming gases is more or less gradual due to the conical portion F which is in the form of a smooth curve.

The sides or peripheral portions of the receiving space are defined by the rear ends 10 g of the series G of equally spaced curved deflecting members or plates. The rear or inner ends g of the several deflecting plates or members coöperate to provide what may be termed a slotted wall that defines the 15 peripheral portion of the initial receiving space and from which wall deflecting plates or members extend outwardly in a manner to guide and control the gases when in transit from the initial receiving space on their 20 way to the conduction chamber. Alternate deflecting members or plates as G^1 are carried on the rear head A while the other set of alternating members or plates as G^2 are carried on the forward head B. These deflecting members or plates are not only carried on the heads as just indicated but in fact are preferably cast on and constitute a 25 part of the member of which the head also constitutes a part. The deflecting members 30 carried by each head extend to the opposite head so that each deflecting member will constitute a vane extending from one head to the other. Alternating deflecting plates being carried by each head permit the 35 deflecting plates to be spaced a sufficient distance apart to allow the making without difficulty of a proper casing.

One of these deflecting members, for instance G_x , extends to the side wall. In fact 40 the member G_x may be considered a continuation of the side wall or the side wall may be considered as a continuation of this particular deflecting member and the two together constitute a part of a spiral starting 45 at X continuing to 1, 2, 3, 4, X^1 , 5, which spiral is a portion extending from X to X^1 that gradually recedes from the center in passing from X to X^1 . The outer ends Y of the deflecting members or plates— 50 with the exception of the member G_x —are all circularly arranged in respect to the center of the initial receiving space E which center is practically coincident with the apex f of the cone F and it will also be observed 55 that said outer ends Y—with the exception of the member G_x —are spaced from the curved side wall C. Between the outer ends of these deflecting members and the side wall C on the one hand and the heads A 60 and B on the other hand there is defined a gradually increasing conduction chamber Z through which the gases flow toward the muffler discharge opening DO in the direction indicated by the arrows $z^1 z^2 z^3 z^4 z_x$. 65 This conduction chamber Z gradually in-

creases in cross-sectional area up to approximately Z^1 after which it is slightly contracted, thus making a construction which is more harmonious in appearance than would be the case if the gradual increase in 70 cross-sectional area of the conduction chamber Z, extended to the muffler discharge opening DO. Moreover, it is desirable to have the area of the discharge more nearly approximate the area of the inlet opening 75 IN that is provided within the tubular projection D. These several deflecting members or plates are uniformly spaced and symmetrically arranged and each is in the form of a spiral. The rear or inner ends of the 80 series G of the deflecting members or plates are spaced so as to provide between them a number of narrow slots $g^1 g^2$, etc., corresponding to the number of deflecting plates between which the gases flow forwardly in 85 passing from the initial receiving space E on their outward path through the muffler and the gases are deflected by the forward ends of these deflecting members or plates so that they make a relatively small angle 90 as rz with the path of flow of the gases along the spiral conduction chamber which last mentioned path is indicated by the arrows $z^1 z^2$, etc.

These deflecting members or plates may 95 be considered to define a series of nozzles at N^1 , N^2 , N^3 , etc. The delivery of gas from the nozzle N^1 , for instance, sucks the gases flowing through the space between the succeeding nozzles as through N^2 ; thereafter the combined effect of preceding nozzles assists in sucking gases from succeeding nozzles or spaces. In other words, the gas from the nozzle N^1 which is in effect farthest from the muffler discharge opening DO must 100 travel along the longest path and is also doing work in assisting the withdrawal of gases from subsequent nozzles. The nozzles are constructed so as to allow the gases to expand to atmospheric pressure or nearly so. 105 They are also constructed so that the suction effect of each preceding nozzle will be taken advantage of as far as possible in assisting the withdrawal of gases through the subsequent nozzles.

As previously indicated the nozzle providing members, to wit, the deflecting members or plates, are curved at their outer ends so that they will discharge the gases into the conduction chamber at a small angle and in 110 a direction to make a smooth, undisturbed flow through the conduction chamber. While it is not absolutely necessary that the discharge ends of the deflecting members—which define the nozzles—be arranged in a 115 circle yet it will be manifest from an inspection of the drawing that this is a practical construction and this is the preferred form. Due to the arrangement shown in Fig. 1 it will be observed that the gases tend 120 to 125 130

to have a uniform flow and expansion from the time they enter the initial receiving chamber E until they are ready for discharge from the conduction chamber Z.

- 5 In the operating of a gas engine it is in the short moment or period from the opening of the exhaust valve—which takes place when the piston is near the bottom of the cylinder—and until the pressure in the cylinder is reduced to atmospheric pressure that the sharp noise results from the exhaust. In this short period the gases at the delivery ends of the nozzles N^1 N^2 , etc., have a higher velocity than in the following discharge of the gases from the cylinder, due to the upward movement of the piston from its bottom position to its highest position. This first sudden blast of gases leaves several nozzles at the same moment but due to the fact that the gases must travel different distances to the delivery end of the conduction chamber, or in other words to the discharge opening of the muffler, the flow from the discharge opening will be more uniform than would be the case if the delivery end of the nozzles were not thus spaced the different distances from the discharge opening. This results in an ironing out or evening of the blast impacts reaching the discharge opening of the muffler and the dividing of the large blast impact into a number of successive small impacts. Moreover, the gases discharged from the nozzles N^1 N^2 , etc., will have a suction effect upon the gases discharged from the subsequent nozzles thus accelerating the flow of the gases from subsequent nozzles and causing a corresponding retardation of the flow of gases from the preceding nozzles, which last-mentioned gases have the longest distance to travel.

It will be observed from Fig. 1 of the drawing that the gases which first pass through, for example, the slots g^1 g^2 , gradually increase in volume in passing toward the delivery end of the nozzles N^1 N^2 and flow into the entrance end of the conduction chamber Z. The cross-sectional area of this conduction chamber gradually increases so that in any particular cross-section in the conduction chamber the area of the cross-section approximates or becomes a function of the combined cross-sectional area of the delivery ends of the preceding nozzles and in this way there is a uniform expansion of the gases from the time they pass the slots g^1 g^2 to the time they are ready for delivery through the discharge opening of the muffler. A line passing through the center F, which will be considered the center of the muffler, and through the inner end of any one of the deflecting members or plates of the series G will show that each deflecting member or plate as a whole is approximately at right angles to said radial line. The inner

end of the deflecting member or plate makes an obtuse angle P with its said radial line while the delivery end of the same deflecting member makes an acute angle R with the same radial line.

70

This angle R is approximately the angle r_2 which the discharge end of this deflecting member makes relative to the path of flow of the gases through the conduction chamber Z. In regard to the construction of the parts so that the flow will be gradually increased from the time of leaving the slotted portion g to the time the gases are ready for discharge from the muffler, this can be readily calculated by a person desiring to construct the muffler so as to embody the invention herein described.

75

In the construction shown the muffler is made in two halves held together by bolts b. The details of construction of the muffler may be readily followed without departing from the spirit and scope of the invention.

80

What I claim is:

1. A muffler of the class described comprising a casing having spaced heads and a spiral side wall, which casing is provided with inlet and discharge openings, said muffler also comprising a series of uniformly spaced deflecting plates one of which plates merges into and becomes a continuation of the spiral side wall, the inner ends of said deflecting plates providing the peripheral portion of a centrally located initial receiving space into which the gases from the inlet opening flow, the outer end portions of said deflecting plates and the wall portion of the casing on the one hand and the spaced heads on the other providing a conduction chamber that gradually increases in cross-sectional area along the line of flow.

90

2. A muffler of the class described comprising in combination spaced heads, a casing side wall, which is a part of a spiral formation one end of which spiral formation extends to the initial receiving space of the muffler, a series of uniformly-spaced deflecting plates the outer ends of which deflecting plates have a circular arrangement and are arranged relatively to the casing side wall so that there is provided a gradual increasing conduction chamber.

100

3. A muffler of the class described comprising in combination spaced heads, a spiral wall formation, deflecting plates which define a centrally located initial receiving space from which incoming gases pass through slots, between the inner ends of said deflecting plates, into the spaces between said deflecting plates, there being between the outer ends of said deflecting plates and the wall formation a conduction chamber leading to the discharge opening of the muffler which conduction chamber gradually increases in cross-sectional area in passing

110

115

120

125

130

toward the discharge opening, the ends of said deflecting plates being constructed and arranged so that each makes an acute angle with the direction of flow of the gases passing by it.

4. A muffler of the class described comprising in combination spaced heads, a spiral-shaped side wall, a series of uniformly spaced deflecting plates the inner 10 ends of which plates define the peripheral portion of an initial receiving space, the outer ends of said deflecting plates being arranged relative to the side wall so that there is between said deflecting plates and said 15 side wall a conduction chamber that gradually increases in cross-sectional area in passing toward a discharge opening of the muffler, each deflecting plate being constructed so that the inner end thereof makes an 20 obtuse angle with the radial line passing through the center of the initial receiving space to the inner end of the deflecting plate, the outer end of said deflecting plate making an acute angle with the same radial 25 line.

5. A muffler embodying a casing having spaced heads and spiral side walls, said muffler also having a series of equally spaced uniformly arranged curved deflecting plates 30 between said heads, the inner ends of which deflecting plates provide the peripheral portion of an initial receiving space or chamber, one of said deflecting plates extending to said wall and in effect becoming 35 a continuation thereof, the outer ends of said deflecting plates and the wall on the one hand and the spaced heads on the other defining a conduction chamber through which the gases flow after passing the deflecting plates on the way to the discharge 40 opening of the muffler.

6. A muffler having a casing which is provided with the necessary inlet and discharge openings, which casing comprises 45 spaced heads and a spiral-shaped inclosing side wall, said muffler having a series of uniformly spaced deflecting members or plates one of which is in effect a continuation of the side wall, the outer ends of said 50 spaced deflecting plates being arranged in a circular path about the center of an initial receiving space, which receiving space is defined by the inner ends of said deflecting plates, and into which initial receiving 55 space the gases are received from the inlet opening of the muffler, the construction being such that between the outer ends of the deflecting member and the spiral side wall there is provided a conduction chamber 60 which gradually increases in volume in passing toward the discharge opening of the muffler.

7. A muffler of the class described comprising a casing having spaced heads and 65 a curved side wall, which casing is provided

with inlet and discharge openings, said muffler also comprising a series of spaced curved deflecting plates one of which merges into and becomes a continuation of the curved side wall, the inner ends of said deflecting plates providing the peripheral portion of a centrally located initial receiving space into which the gases from the inlet opening flow, the outer end portions of said 70 deflecting plates and the wall portion of the 75 casing on the one hand and the spaced heads on the other providing a conduction chamber leading to the discharge opening.

8. A muffler of the class described comprising in combination spaced heads, a casing side wall, a series of uniformly-spaced curved deflecting plates one of which extends to or merges into the side wall and the others of which are arranged so that the outer ends thereof are spaced from the 85 casing side wall whereby there is provided a conduction chamber leading to the muffler discharge.

9. A muffler of the class described comprising in combination spaced heads, a 90 curved side wall, a series of uniformly-spaced deflecting plates or members extending outwardly from a slotted wall defining the peripheral portion of an initial receiving space, the outer ends of said deflecting 95 plates being arranged relative to the side wall so that there is between said deflecting plates and said side wall a conduction chamber leading toward a discharge opening of the muffler, each deflecting plate being 100 constructed so that the inner end thereof makes an obtuse angle with the radial line passing through the center of the initial receiving space to the inner end of the deflecting plate, the outer end of said deflecting plate making an acute angle with the same radial line, one of said deflecting plates or members being constructed so that it extends to the side wall.

10. A muffler having a casing which is 110 provided with inlet and discharge openings, which casing comprises spaced heads and a curved inclosing side wall, said muffler having a series of uniformly-spaced deflecting members or plates one of which is in effect 115 a continuation of the side wall, the outer ends of the other of said spaced deflecting plates being spaced from said inclosing side wall, said muffler having an initial receiving space into which the gases are received 120 from the muffler inlet opening, which inlet or receiving space is partially defined by the inner ends of said deflecting plates, the muffler construction being such that between the outer ends of the deflecting members and the side wall there is a conduction chamber for the gases flowing toward the discharge opening.

11. A muffler having a casing provided with inlet and discharge openings, which 130

casing comprises spaced heads and an inclosing side wall, said muffler having a series of spaced deflecting members or plates one of which extends to the side wall, the outer ends of the other of said spaced deflecting plates being spaced from said inclosing side wall, said muffler having an initial receiving space into which the gases are received from the muffler inlet opening, the peripheral portion of which inlet or receiving space is defined by a slotted wall, the muffler

construction being such that between the outer ends of the deflecting members and the side wall there is a conduction chamber for the gases flowing toward the discharge opening.
